INTAKE MANIFOLD STRUCTURE

Victor R. Heftler, Detroit, Mich., assignor, by
mesne assignments, to Zenith Carburetor Com-
pany, Detroit, Mich., a corporation of Michigan

Application January 20, 1932, Serial No. 587,695

12 Claims. (Cl. 123—122)

The present invention relates broadly to the art of internal combustion engines, and more particularly to improved means for the supply of a combustible mixture thereto under different operating conditions.

In the operation of multi-cylinder internal combustion engines of usual construction, there is provided an intake manifold of such construction as to effectively cooperate with each of the various cylinders at one end and to receive a carburetor at the opposite end. In the majority of cases such manifolds are of constant cross sectional area, and the only control for the actual combustible mixture is that afforded by the carburetor throttle. With such structures, and with the throttle only partly or slightly opened, the flow area of the manifold is considerably greater than that required for handling the quantity of mixture which the throttle valve at its then position will pass. This results in an accelerated flow past the throttle followed by a decrease in velocity in the main body of the manifold.

This decrease in velocity is objectionable for a number of reasons, two of which, however, are perhaps more important than the others. In the first place, the decrease in velocity, and particularly with a relatively cold motor, results in the deposit of a portion of the fuel from the air stream so that the engine does not receive the desired fuel quantity or mixture.

In the second place, the decrease in velocity results in objectionable eddy currents or non-uniform flow conditions in different portions of the manifold, which conditions are frequently reflected in a non-uniform distribution to the different cylinders. Regardless of the exact causes which contribute to the variation in performance of a given manifold under different operating conditions, it is a fact that a manifold which operates most efficiently at low speeds is not capable of operating at maximum efficiency at high speeds, and vice versa. This necessitates providing a manifold which is usually at least in part a compromise capable of more or less efficiently serving the motor throughout its entire operating range.

It has heretofore been proposed, in an effort to provide a more efficient fuel supply system, to construct a manifold of such nature that its flow area could be increased or decreased to correspond to different positions of the throttle by physically changing the size of a single flow passage or conduit, or by bringing successive conduits into operation. Such structures have in part solved the difficulties attendant upon the

use of standard intake manifold structures, but their added cost as compared to the advantages gained has not been such as to justify much more than experimental use thereof.

It will be apparent that any construction requiring a physical change in the flow area of a single conduit is objectionable due to the complicated structure provided for effecting the necessary adjustment of the parts and the difficulties attendant upon maintaining the desired tightness of the various joints. For these reasons a divided manifold providing a plurality of flow passages is preferable, and it is to such a construction that the present invention relates.

Inasmuch as efficient distribution and motor operation dictate the desirability of supplying a mixture, preformed, through all of the various flow passages of the manifold, it is desirable that these conduits all receive, at one end, a mixture of certain predetermined characteristics. This may be most effectively accomplished by the utilization of a single carburetor adjusted to supply the desired mixture and assembling the various conduits in such manner that all of the conduits will be supplied from such carburetor.

If the control with respect to the number of conduits in use at any time is left under the control of the operator, it is not only possible, but probable, that throughout the major portion of the operation of the motor the adjustment made by the operator will not be theoretically correct for the actual flow, thus defeating the full advantages of a divided manifold. To this end I provide means responsive to engine conditions for automatically controlling the flow area at any instant, while always providing a flow conduit of minimum cross sectional area capable of giving efficient low speed performance.

The art has heretofore recognized the advantages of preheating a combustible mixture as supplied to a motor. This preheating also involves difficulties. If a single manifold is made large enough to supply the maximum volume required by the motor at any time with the entire mixture heated, it is unduly large for any low speed operation. If it is made small enough for efficient low speed operation with a heated charge, the top speed of the engine cannot be obtained. My invention therefore contemplates not only a divided manifold, but a manifold characterized by divisions which may be operated at different temperatures, the construction preferably being such that there is a comparatively high temperature charge supplied for low speed operating conditions with a relatively lower temperature

charge at all higher speeds. This condition may be effectively obtained by providing a manifold having conduits adapted to supply a mixture at relatively different temperatures and so con-

5 tructed that the highest temperature conduit is always open to provide a flow passage of definite predetermined area extending from the carburetor to the motor. To this end the construction preferably comprises a constantly open relatively 10 hot conduit with a normally closed relatively cold conduit, which relatively cold conduit may be opened more or less automatically in accordance with the requirements of the engine.

I have further found that with an automatic 15 control, such as one responsive to suction conditions above the throttle, it is desirable to preclude the possibility of any excessively rapid change in the position of the control valve with consequent "chattering" of the valve and corresponding pulsations in the mixture being supplied. To preclude such a possibility, I preferably provide a valve responsive to suction, but controlled in part through the medium of a dash-pot effective for dampening or checking excessively rapid movements thereof.

In the accompanying drawings I have shown for purposes of illustration only, certain preferred embodiments of my invention. In the drawings:

30 Figure 1 is a side elevational view, partly broken away, of a manifold constructed in accordance with the present invention;

Figure 2 is a side elevational view of the relatively cold conduit and control casing;

35 Figure 3 is a front elevational view of the structure of Figure 2;

Figure 4 is a bottom plan view of the structure of Figures 2 and 3;

40 Figure 5 is a vertical sectional view on an enlarged scale through the valve casing of Figures 2 and 3;

Figure 6 is a partial top plan view, partly broken away, of a portion of the exhaust manifold showing the relatively hot manifold formed integrally therewith;

45 Figure 7 is a transverse sectional view on the line VII—VII of Figure 6;

Figure 8 is a top plan view of the carburetor riser;

50 Figure 9 is a side elevational view of the carburetor riser;

Figure 10 is a transverse sectional view on the line X—X of Figure 1; and

55 Figure 11 is a detailed sectional view illustrating a slightly modified form of closure for the upper end of the valve casing.

In accordance with the present invention, there is provided an exhaust manifold 2 of any usual construction but preferably having formed integrally therewith a conduit 3, as illustrated more 60 particularly in Figure 6, adapted to constitute the relatively hot conduit of an intake manifold. At substantially its mid portion, the conduit 3 is shaped to provide a lower flange 4 adapted to cooperate with the upper flange 5 of a carburetor

65 riser 6 illustrated in Figures 8 and 9. Opposite the flange 4 the conduit 3 is formed with an upper flange 7, as shown in Figure 6, adapted to receive a flange 8 formed on a relatively cold conduit as illustrated more particularly in Figure 4 of the drawings.

70 Extending continuously between the flanges 4 and 7 is a through passage 9 adapted to align with the passage 10 through the carburetor riser 6 and to align with a passage 11 in a valve casing 12 formed integrally with the flange 8 of the rel-

atively cold conduit. Formed in diametrically opposite sides of the through passage 9 are ports 14 leading to the opposite flanges of the relatively hot conduit 3.

The riser 6 is in turn formed with a bottom flange 15 adapted to cooperate with the upper flange 16 of a carburetor 17 of any desired construction.

5 The relatively hot conduit 3 is formed with extensions 18, as illustrated in Figure 1, projecting downwardly a sufficient distance to cooperate with the intake ports of a motor, as in usual structures. Extending laterally from the valve casing 12 are similar passages 19 of such length as to cooperate with the extensions 18 and also 15 deliver a combustible mixture to the inlet ports of the motor, the extensions 19 being provided with attaching flanges 20 for securing the same in position. These extensions 19 communicate with the valve casing through diametrically opposite ports 21, which ports are so disposed as to lie in the path of travel of a valve 21a disposed within the valve casing. This valve is illustrated in Figure 5 as comprising a piston carried by a stem 22 extending through a second piston 23. 25 The pistons 21a and 23 are disposed within the valve casing 12 on opposite sides of a stop ring 24 adapted to be held in position by screws 25.

Carried by the stop ring is a centering sleeve 30 26 through which the stem 22 moves. Bearing 30 at one end against the sleeve 26 and at its opposite end against the underside of the upper piston 23 is a spring 27 normally tending to urge the parts into the position illustrated in Figure 5. Also cooperating at its lower end with the sleeve 35 26 is a second spring 28 of relatively lighter construction than the spring 27 and of less length and serving to check downward movements of the valve 21 as will be hereinafter more clearly apparent.

40 The upper end of the valve casing 12 is closed by a cap 29 having a port 30 therethrough communicating with the atmosphere and subjecting the upper surface of the piston 23 to atmospheric pressure. It will be apparent that with the parts 45 assembled, the underside of the piston valve 21a will be subjected to suction conditions existing within the manifold at a point intermediate the engine and the carburetor throttle (not shown) provided on the throttle shaft 31. Due to this 50 construction, if the throttle is in its partly opened position as in the case of idling or slow speed running, there will be a comparatively high vacuum, or low absolute pressure in the space intermediate the throttle and the engine. This pressure will, in any case, be sufficiently lower than atmospheric pressure so that the atmospheric pressure existing on the upper surface of the upper piston 23 will lower this piston against the action of the spring 27 and thereby lower the 55 piston valve 21a into a position where it will cover the ports 21 and thereby cut off communication between the carburetor and the extensions 19 of the relatively cold manifold.

60 During the lowering movement of the pistons, the upper end of the inner spring 28 will come into engagement with a washer 32 and thereby cushion the further downward movement of the pistons. This downward movement will ultimately be checked either by the engagement of 65 the skirt 33 of the piston 23 with the upper side of the stop ring 24, or by the engagement of a stem collar 34 with the upper end of the sleeve 26, depending upon the setting of the parts. In either case the maximum movement of the pistons 70 75

in both directions will be definitely controlled. The extent of upward movement is preferably only such that the ports 21 may be completely uncovered while the extent of downward movement is slightly greater than that required to completely close such ports. In no case does the piston valve 21a pass into the through passage 9 of the relatively hot conduit so as to interfere with the free flow of a mixture from the carburetor into the through passage and thence by way of the ports 14 to the relatively hot conduit 3 and the extensions 18 to the inlet chambers of the motor. If desired the through passage may terminate in a flange 35, as shown in Figure 7, so as to provide a small ledge or shoulder underlying the valve chamber and provide a definite further limit to the downward movement of the piston valve 21a.

By reason of the construction described, it will be apparent that when a motor is started into operation, or when it is continued in operation at a relatively low speed requiring only a relatively small volume of flow to the motor, the relatively cold conduit will be cut off from communication with the motor by the piston valve 21a, thereby enabling a combustible mixture to be furnished from the carburetor through the riser 6 to the motor only by way of the relatively hot conduit 3. This conduit will be initially designed with a flow area such as to insure desirable flow conditions to the motor and with sufficient flow area so as to furnish the motor with the desired mixture during low speed operation thereof.

If the throttle is suddenly opened, the absolute pressure in the intake manifold between the throttle and the motor will rise to such an extent that the suction will not be great enough to hold the piston valve 21a in its lower position against the action of the spring 27. The pistons 21a and 23 will therefore move into the position shown in Figure 5 with a speed of movement directly controlled by the rapidity with which the air above the piston 23 is permitted to escape through the atmospheric vent 30. By making this vent sufficiently small, the upward movement of the piston assembly may be effectively controlled.

At intermediate throttle positions, the valve 21a may assume intermediate positions corresponding more or less exactly to the suction conditions within the manifold, thereby providing a flow area through the relatively cold conduits which is directly proportioned, automatically, to the engine requirements.

In some cases it may be desirable to so restrict the upward movement of the valve assembly until such time as the temperature adjacent the motor, or under the hood in the case of an automobile, has reached a predetermined point. If such is the case, I may utilize the construction illustrated in Figure 11 wherein there is shown a modified form of cap 29' for the valve chamber. In this embodiment the cap is formed with a through opening 36 into which is threaded a valve holder 37 provided with a port 38 terminating in a seat 39 from which projects a valve retaining sleeve 40.

Within the valve retaining sleeve is a ball valve 41 normally held in the position illustrated in Figure 11 by a bi-metallic finger 42. As the temperature to which the bi-metallic finger 42 is subjected rises, the finger will bend downwardly, thereby lowering the valve 41 within its sleeve 40. As long, however, as the temperature is below a certain predetermined point for which the bi-metallic strip 42 is set, the valve 41 will be held

against the seat 39. In this position the upward movement of the piston assembly will be precluded. Downward movement, however, will be permitted to the extent required to permit lowering of the piston assembly within the casing 12. During such lowering movement, atmospheric pressure will unseat the valve 41 against the action of the bi-metallic finger 42 and permit atmospheric pressure to flow past the valve and through the ports 43 into the valve chamber 12.

With this construction, it is possible to continue operation of the motor utilizing only the relatively hot conduit 3 until such time as the entire motor has reached a predetermined operating temperature sufficient to insure deflection of the finger 42.

Under normal conditions of operation, assuming the motor to have reached an operating temperature, it will be supplied during idling and low speed entirely through a relatively hot conduit of fixed cross sectional area which is always freely open to provide free communication between the carburetor and the motor and effective for delivering a combustible mixture from the carburetor to the motor in heated condition, due to the intimate heat transfer relationship between the conduit 3 and the exhaust manifold 2. When, however, the operating conditions of the motor require a greater mixture flow, the valve assembly including the valve 21, will automatically rise to the extent determined by the increase in absolute pressure within the manifold corresponding to the position of the throttle.

To this extent there will be provided an auxiliary flow conduit in parallel with the relatively hot conduit and communicating at its opposite ends respectively with the carburetor and motor with which the relatively hot conduit communicates. The auxiliary flow conduit, therefore, will be effective for delivering a combustible mixture of the same characteristics as that supplied by the relatively hot constantly open conduit, the mixture at different temperatures uniting in the inlet chambers of the motor from which it is supplied to the cylinders.

It will be apparent that the relative areas of the conduits 3 and 19 may be varied at the will of the designer and in accordance with the constructional and operating characteristics of the motor with which the manifold is utilized, whereby the relatively hot constantly open conduit may either be equal in its flow area to that of the auxiliary conduit or may have a less area or greater area than the flow conduit. In most cases, however, I have found that the most satisfactory results are obtained by providing a relatively hot conduit having a flow area which does not exceed that of the auxiliary conduit and which is preferably somewhat less than that of the auxiliary conduit. In this manner a higher velocity flow of heated mixture is rendered available for all idling and low speed running periods of the motor.

The advantages of the invention arise from the provision of an intake manifold adapted to receive a combustible mixture from a carburetor and deliver it to an engine, and characterized by the division of the manifold into a plurality of relatively separate conduits terminating at one end in a position adjacent a carburetor throttle and at the opposite end communicating with the inlet chamber or chambers of an internal combustion engine, with one of the conduits continuously open to provide a fixed flow area for idling and low speed running conditions, together

with means responsive automatically to engine requirements for controlling the number of conduits in excess of the constantly open conduit which are available at any time.

5. Further advantages arise from a construction of the character described effective for providing a constantly open conduit for furnishing the mixture to the motor at relatively high temperature during such periods of time as full power from 10 the motor is not required. In this manner there is obtained an efficient vaporizing of the liquid fuel at low speeds. At high speeds, if the single conduit were utilized, the heating of the charge would so expand the air that a given unit of volume would have materially less weight than that required for full power. In accordance with the 15 present invention, when full speed is desirable, a supplemental conduit automatically comes into operation thereby furnishing the full volume and 20 weight of air required for such operating conditions.

Still further advantages arise from the provision of automatic controlling means so constructed and regulated as to preclude undesirable 25 chattering or hammering movements thereof.

While I have herein illustrated and described certain preferred embodiments of the invention, it will be understood that changes in the construction and operation of the parts may be made 30 without departing either from the spirit of the invention or the scope of my broader claims.

I claim:

1. The combination with a carburetor, of a manifold adapted to receive a combustible mixture from the carburetor and deliver it to an engine, characterized by the division of the manifold into a plurality of separate conduits, a throttle valve intermediate the carburetor and the manifold, one of said conduits being continuously open, and means responsive to the difference between atmospheric pressure and the pressure in the manifold for controlling the number of conduits additionally to said constantly open conduit which are available at any time for 45 mixture delivery.

2. The combination with a carburetor, of a manifold adapted to receive a combustible mixture from the carburetor and deliver it to an engine, characterized by the division of the manifold into a pair of separate conduits, a throttle valve intermediate the carburetor and the manifold, one of said conduits being continuously open, and means responsive to the suction of the engine between the throttle and engine and exposed to the atmosphere for controlling the flow 50 through the second conduit of said pair.

3. The combination with a carburetor, of a manifold adapted to receive a combustible mixture from the carburetor and deliver it to an engine, characterized by the division of the manifold into a pair of separate conduits, a throttle valve intermediate the carburetor and the manifold, one of said conduits being continuously open, and means responsive to the suction of the engine between the throttle and engine for controlling the flow through the second conduit of 55 said pair, said means comprising a valve movable in response to the suction to which it is subjected, said valve having one side only in communication 60 with the engine.

4. The combination with a carburetor, of a manifold adapted to receive a combustible mixture from the carburetor and deliver it to an engine, characterized by the division of the manifold into 75 a pair of separate conduits, a throttle valve in-

termidiate the carburetor and the manifold, one of said conduits being continuously open, means responsive to the suction of the engine between the throttle and engine for controlling the flow through the second conduit of said pair, and means for regulating the speed of movement of said conduit controlling means.

5. The combination with a carburetor, of a manifold adapted to receive a combustible mixture from the carburetor and deliver it to an engine, characterized by the division of the manifold into a plurality of separate conduits, a throttle valve intermediate the carburetor and the manifold, one of said conduits being continuously open, means responsive to the operation of the engine for controlling the number of conduits additionally to said constantly open conduit which are available at any time for mixture delivery, and means for regulating the speed of movement of said conduit controlling means.

6. The combination with a carburetor, of a manifold adapted to receive a combustible mixture from the carburetor and deliver it to an engine, characterized by the division of the manifold into a plurality of separate conduits, a throttle valve intermediate the carburetor and the manifold, one of said conduits being continuously open, and means responsive to the suction of the engine between the throttle and engine for controlling the number of conduits additionally to said constantly open conduit which are available at any time for mixture delivery, said means comprising a valve having one side exposed to the atmosphere.

7. The combination with a carburetor, of a manifold adapted to receive a combustible mixture from the carburetor and deliver it to an engine, characterized by the division of the manifold into a plurality of separate conduits, a throttle valve intermediate the carburetor and the manifold, one of said conduits being continuously open, means responsive to the suction of the engine between the throttle and engine for controlling the number of conduits additionally to said constantly open conduit which are available at any time for mixture delivery, and means for regulating the speed of movement of said conduit controlling means.

8. The combination with an exhaust manifold having secured thereto in heat conducting relationship an intake conduit provided with a plurality of branches terminating adjacent to the intake valves, of a carburetor adapted to supply a combustible mixture to said conduit, a throttle valve intermediate the carburetor and said conduit, a second conduit extending generally parallel to said first mentioned conduit throughout adapted to receive a mixture supply from said carburetor, said second conduit being in less efficient heat transfer relationship to the exhaust manifold than the first conduit, means cooperating with said second conduit only for controlling the effective flow area thereof, said last mentioned means comprising a control valve automatically movable in response to the operation of the engine supplied by said carburetor, and means for controlling the movement of said valve.

9. The combination with an exhaust manifold having an intake conduit secured thereto in heat conducting relationship, a carburetor adapted to supply a combustible mixture to said conduit, a throttle valve intermediate the carburetor and said conduit, a second conduit adapted to receive a mixture supply from said carburetor, said second conduit being in less efficient heat transfer

relationship to the exhaust manifold than the first conduit, means cooperating with said second conduit only for controlling the effective flow area thereof, said last mentioned means comprising a control valve automatically movable in response to the operation of the engine supplied by said carburetor, and thermostatically operated means for controlling the movement of said valve.

5 10. An intake manifold comprising a plurality of conduits connected in parallel and adapted to communicate with a carburetor at one end and deliver a combustible mixture to an engine at the other end, and means including a dash-pot and valve therein automatically responsive to the operation of the engine to which said manifold is attached for controlling the flow area of one 15 of said conduits only.

11. An intake manifold comprising a plurality of conduits connected in parallel and adapted to communicate with a carburetor at one end and deliver a combustible mixture to an engine at the other end, and means including a dash-pot 20

and valve therein automatically responsive to the operation of the engine to which said manifold is attached for controlling the flow area of one of said conduits only, there being means for heating one of said conduits to a higher temperature than the remaining conduit.

12. The combination with a carburetor, of a manifold adapted to receive a combustible mixture from the carburetor and deliver it to an engine, characterized by the division of the manifold into a plurality of separate conduits, a throttle valve intermediate the carburetor and the manifold, one of said conduits being continuously open, and means including a valve having one side under the influence of the mixture pressure and the other side outside the influence of the mixture pressure for controlling the number of conduits additionally to said constantly open conduit which are available at any time for mixture delivery.

10 15 20 VICTOR R. HEFTLER.
